UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

BRAKE-HANGER BRACKET.

Application filed February 17, 1923. Serial No. 619,776.

To all whom it may concern:

Be it known that I, BYERS W. KADEL, a citizen of the United States, residing at Baltimore, in the State of Maryland, have invented certain new and useful Improvements in Brake-Hanger Brackets; and I do hereby declare the following to be a full, clear, and exact description of the invention, such as will enable others skilled in the art to which it appertains to make and use the same.

My invention relates to car trucks and more particularly to a brake hanger bracket or carrier.

The principal feature of the invention, generally stated, resides in the provision of a strong, durable and efficient brake hanger bracket formed with a plurality of connecting portions advantageously located with respect to the main supporting web of the bracket, said connecting portions being also arranged for engagement with the adjacent portions of the truck columns and compression member of the side frame.

Particularly stated, the invention consists in providing a brake hanger bracket adapted for attachment to a wrought metal side frame wherein it is desirable to rigidly support the brake hanger bracket and mount the brake hangers within the standard A. R. A. limits, and at the same time provide for sufficient clearance between the bolster and bracket.

Another object of the invention is to provide a brake hanger bracket including a plate portion and projecting channel-shaped web, the latter being provided with an extending trunnion located adjacent an opening in the web whereby the looped supporting end of the brake hanger is mounted relatively close to the bolster opening and is permitted to move within said opening clear of any contact with the said web.

A further feature of the invention is to provide a brake hanger bracket composed of an attaching plate portion and an inwardly extending brake hanger supporting portion, said supporting portion including a vertically disposed web having a cut away portion therein, a projection extending from one side of the web toward the bolster opening with which the bolster may contact, and means extending from the opposite side of said web adjacent said cut away portion for supporting the hanger with its looped end extending into said cut away portion.

The invention further consists in arranging the vertically disposed web of the brake hanger supporting portion and reinforcing the same by continuing portions thereof about an attaching point of the bracket and otherwise reinforcing the supporting web with relation to other of the attaching portions.

With these and other objects in view, the invention further consists in the combination, construction and arrangement of the several parts hereinafter described and pointed out in the claims.

In the drawings:

Figure 1 is a side view of my improved brake hanger bracket shown attached to a portion of a car truck side frame, portions of the bolster and brake hanger being shown in dotted lines.

Figure 2 is a detached view illustrating in side elevation the opposite side of the brake hanger.

Figure 3 is an end view of the bracket shown attached to a portion of the side frame and illustrating the looped ends of the brake hanger attached thereto.

Figure 4 is a plan view of the bracket shown in Figure 3, a portion of the bolster being illustrated to emphasize the clearance between one face of the bracket and said bolster.

Figure 5 is a horizontal sectional view taken on the line 5—5 of Figure 3.

Referring to the drawings wherein similar reference characters designate corresponding parts in the several views, my improved construction of brake hanger bracket is shown attached to the side frame 1, the latter involving the usual compression member 2, truck columns 3 and tension member 4. Pedestal tie bar portions 5 may also be provided, all of said parts being disposed in the usual manner with relation to the bolster opening 6, portions of the bolster being indicated in dotted lines in some of the views.

My present construction of brake hanger bracket includes a base or attaching plate portion 7 having an intermediate offset portion 7' preferably suitably spaced from the side wall of the side frame, as shown in Figure 3. The upper part of the plate attaching portion 7 is provided with a plurality of openings 8 adapted to receive connecting rivets 9. The rivet openings are preferably formed in thickened portions 10 of the plate

section and are disposed upon either side of the vertical reinforcing rib 11 extending inwardly of the side frame. The rib 11 serves to unite the upper portion of the plate section 7 with the upper part of the brake hanger supporting portion of the bracket to be presently described. The lower portion of the plate section 7 is provided with an opening 12, said opening being adapted to receive one of the rivets 9. The rivet opening 12 is preferably located adjacent a strong portion of the truck column, that is to say, the lowermost attaching portion of the bracket is located below the narrowest portion of said truck column portion. In addition, the lowermost rivet opening 12 is preferably disposed longitudinally intermediate the rivet openings 8 in the upper part of the plate section of the bracket, said rivet openings 8 being preferably arranged adjacent relatively large cross sectional areas of the compression member 2.

The brake hanger attaching portion of the bracket involves a channel-shaped portion consisting of the vertically disposed web 13, an upper flange 14, and a lower flange 15, both of said flanges projecting away from the bolster, and the lowermost of said flanges being smaller and arranged to underlie the uppermost of said flanges. Projecting from the vertical web 13 are integral extensions 16 and 17, said extensions being suitably reinforced and otherwise disposed to form the trunnions which receive the hanger pin. The pin is shown at 18 in dotted lines in Figure 3 as supporting the brake hanger and more especially the arms 19 thereof, the usual washers 22 and cotter pin 23 being also illustrated by dotted lines.

The vertical web 13 of the hanger supporting portion of the bracket is provided with an opening or aperture 20, said opening extending above and below the center line of the hanger pin and being arranged adjacent the trunnion extension 16. In my present embodiment I have shown an elongated aperture, although it will be understood that various other forms of cut-away portions, openings, slots, and shapings may be used to effect the clearance of the upper looped end of the brake hanger arm supported adjacent the trunnion 16. Upon the face of the web 13 adjacent the bolster and more especially within the limits of movement of the cover plate thereof, is provided a bead or projecting portion 21, said bead in addition to strengthening the metal immediately adjacent said opening being also adapted to receive and indicate the wear as imparted to the brake hanger bracket from the bolster cover plate. By this means of tell-tale portion or bead formation, it will be seen that observations of the wear can be noted from time to time as affecting the service requirements demanded of these

and other associated portions of the equipment. By means of cutting away portions of the web 13 it will be seen that the center of support of the brake hangers can be maintained within standard limitations and at the same time the full supporting strength of the bracket, and especially of said web, can be utilized, it also being observed that by this construction maximum clearance between the bolster and brake hanger bracket is maintained.

The vertical web 13 at its lower end is preferably continued around a portion of the rivet opening 12, said rivet opening being preferably located to one side of the center of said web. One of the rivet openings 8 in the upper part of the plate attaching portion is located upon the opposite side of a vertical center passing through the web 13. The arrangement of these attaching portions of the bracket upon substantially opposite sides of the vertical web supporting the trunnions, acts to provide a very strong and effective connection, it being observed that while said connecting rivets are vertically offset, the amount of said offset is relatively slight and somewhat dependent upon the thickness and disposition of the vertical web. The offset arrangement of the reinforcing rib 11 with respect to the vertical web 13, and its intermediate location between the rivets passing through the openings 8, serves to complement the vertical supporting strength of the bracket in beam-like action through the upper flange 14 of the channel-shaped brake hanger supporting portion of the bracket.

Having thus described my invention, I claim:

1. A brake hanger bracket comprising a plate section provided with a plurality of attaching portions, at least one of said portions being connected to the truck column of the side frame, and other of said portions being connected to the compression member of the side frame, and a brake hanger supporting portion projecting from said plate section and extending inwardly of the side frame, said supporting portion including a vertical web disposed intermediate said attaching portions and a plurality of webs extending outwardly from said vertical web.

2. A brake hanger bracket involving an attaching portion, a brake hanger supporting portion including a channel-shaped web extending from said attaching portion, and trunnions provided on said web intermediate the upper and lower flanges of said channel-shaped web, said web being provided with an opening adjacent at least one of said trunnions.

3. A brake hanger bracket comprising an attaching portion, and an integral brake hanger supporting portion, and trunnions provided on said brake hanger supporting

portion, said brake hanger supporting portion being formed with a cut-away portion adjacent at least one of said trunnions to provide for clearance between the looped end 5 of at least one of the brake hanger arms and an adjacent portion of the supporting portion.

4. A brake hanger bracket including an attaching plate portion, an integral brake 10 hanger supporting portion, flanges provided on said brake hanger supporting portion and adapted to extend away from the bolster, the lowermost of said flanges being of less width than the uppermost flange, trunnions 15 provided on the brake hanger portion for supporting a brake hanger, and means including an opening provided in said brake hanger attaching portion adjacent at least one of the trunnions, said opening and relatively narrow lower flange being adapted to 20 provide clearance for full swinging movement of the brake hanger.

5. A brake hanger bracket comprising an attaching portion and an inwardly extending 25 brake hanger supporting portion, trunnions provided on said brake hanger supporting portion for mounting a brake hanger, means including an opening adjacent at least one of said trunnions, said opening 30 providing clearance for the looped supporting end of the brake hanger, and means adjacent said opening and projecting in close proximity to the bolster, said last named means being adapted to receive some of the 35 wear incident to the movement of the bolster.

6. A brake hanger bracket adapted to be 40 connected to a side frame, trunnions provided on said bracket and relatively closely spaced from the bolster guides, and means including an opening provided in a vertical portion of the bracket and adjacent one of said trunnions, said opening serving to permit the looped end of at least one arm of the 45 brake hanger to swing adjacent its supporting trunnion without contacting said bracket and further permitting the center of the trunnions to be arranged in said closely spaced relation to the bolster guide.

50 7. A brake hanger bracket having an attaching portion, a brake hanger supporting portion including a web arranged in relatively close proximity to one side of the bolster and formed with a cut-away portion, and a brake hanger trunnion having its center arranged in relatively close proximity to said web whereby the looped end of the 55 brake hanger is permitted to swing in said cut away portion and out of contact with said web.

60 8. A brake hanger bracket having an attaching portion, a brake hanger supporting portion projecting inwardly from said attaching portion, a web provided on said attaching portion and having a cut away portion,

tion therein, said web being arranged in relatively close proximity to the bolster, a trunnion having its center in relatively close proximity to said bolster whereby the upper end of the brake hanger is adapted to swing 70 in said cut away portion and clear of said web, and means including a projection provided on said web, said projection being arranged in close proximity to the bolster for receiving wear incident to the movement 75 of said bolster under service conditions.

9. A brake hanger bracket comprising a plate section having a plurality of attaching portions, a brake hanger supporting portion including a vertical web provided with an opening, said web being disposed between some of said attaching portions and having its lower end extending partially about another of said attaching portions, and trunnions provided on said web, the center of 80 said trunnions being located in close proximity to said web whereby the looped end of at least one of the arms of the brake hanger is adapted to move within the opening formed in said web.

10. A brake hanger bracket including an upper attaching portion provided with a plurality of rivet openings and a lower attaching portion provided with a rivet opening, the lowermost rivet opening being arranged intermediate the upper rivet openings, a vertical web arranged intermediate said lowermost rivet opening and one of the uppermost rivet openings and a brake hanger supporting portion disposed intermediate 90 said upper and lower rivet openings.

11. A brake hanger bracket including an upper attaching portion provided with a plurality of rivet openings and a lower attaching portion provided with a rivet opening, the lowermost rivet opening being arranged intermediate the upper rivet openings, a vertical web arranged intermediate 95 said lowermost rivet opening and one of the uppermost rivet openings, a brake hanger trunnion provided on said web, and means including a cut-away portion formed in the web, said cut away portion serving to permit the upper looped end of at least one 100 arm of the brake hanger to swing without contacting said bracket.

12. A brake hanger bracket having a vertically disposed web provided with a cut-away portion, and means for pivotally supporting a brake hanger, said cut-away portion being adapted to permit the location of the pivotal mounting of the hanger relatively close to said web and provide for free movement of the hanger loop without contacting said web.

13. A brake hanger bracket having a web provided with a cut away portion, a projection adjacent said cut-away portion upon one side of the web, and means projecting 130

from the other side of the web adjacent said cut-away portion for supporting the looped end of the brake hanger.

14. A brake hanger bracket having a vertical web provided with a cut away portion, and means projecting from one side of said web and adjacent said cut away portion for supporting the pivotal end of a brake hanger with at least a portion thereof extending 10 in said cut-away portion.

15. The combination with a side frame having a top arch bar portion and integral truck column portions, and a brake hanger bracket having a plurality of portions 15 adapted to be connected to said top arch bar portion and another portion to be connected to the truck column portions, said bracket being formed with a brake hanger supporting portion disposed intermediate the portion 20 of the bracket connected to the truck column and one of the bracket portions connected to the top arch bar.

16. The combination with a side frame including a compression member, a tension 25 member and truck columns, of a brake hanger bracket connected at a plurality of points to said compression member and at one point to said truck columns, a brake hanger supporting portion provided on said bracket, 30 and means including a cut away portion formed in said supporting portion for permitting movement of the pivotal end of the hanger without contacting said supporting

portion, said cut-away portion serving to permit the location of the pivotal connection of the hanger relatively close to the edge of the truck column portion adjacent the bolster opening. 35

17. The combination with a side frame 40 having a bolster opening, of a brake hanger bracket having a web provided with a cut away portion, and means projecting from one side of said web adjacent said cut-away portion for supporting a looped end of the brake hanger, said cut away portion permitting the location of the said looped end relatively close to the bolster opening without contacting said web. 45

18. The combination with a side frame 50 having a bolster opening, of a brake hanger bracket connected to said side frame and having a vertical web portion formed with a cut-away portion disposed relatively close to said bolster opening, means including a projection extending from said web toward the bolster opening, said projection being adapted to receive wear from movement of the bolster, and means projecting from said web and extending away from the bolster opening for supporting the looped end of the 55 brake hanger, said means being located adjacent said cut-away portion whereby the looped end of the hanger may move within said cut-away portion. 60

In testimony whereof I affix my signature.
BYERS W. KADEL.
